DRAFT RIGGING

Norman B. Akitt, Rochester, N. Y., assignor to
 The Symington Company, New York, N. Y., a
 corporation of Maryland

Application June 29, 1929, Serial No. 374,755

5 Claims. (Cl. 213—69)

This invention relates to draft rigging, and more particularly to a coupler stem formed in two parts connected for relative pivotal movement.

5 The principal object of my invention, generally considered, is to provide a coupler with a stem formed in two parts connected for permitting angling of the coupler head, said stem being slotted for receiving a key for connection with an associated yoke and formed with a pocket receiving a shim adapted to engage the front edge of said key for transmitting buffing forces thereto.

10 Another object of my invention is to provide a coupler, the stem of which involves a plurality of parts pivotally connected together and slotted for receiving a draft key for connection with an associated yoke, the forward portion of said slot being enlarged for receiving a shim adapted to seat on the front edge of said key, the front surface of said shim being curved coaxially with the pivotal connection between the parts of the stem, whereby angular motion is permitted between the stem and shim, said shim serving to transmit 15 buffing forces from the coupler to the key and from thence to associated cheek plates and/or draft sills for protecting associated cushioning mechanism from excessive buffing forces.

20 Other objects and advantages of the invention relating to the particular arrangement and construction of the various parts will become apparent as the description proceeds.

25 Referring to the drawing illustrating my invention, the scope whereof is defined by the appended claims.

Figure 1 is a partial plan and partial horizontal sectional view of railway draft rigging embodying my invention.

30 Figure 2 is a central vertical longitudinal sectional view of the stem of the coupler shown in Figure 1.

35 Figure 3 is a horizontal sectional view of the stem of the coupler with the swivel block, pivot pin, key and shim removed on the line 3—3 of Figure 2, looking in the direction of the arrows.

40 Referring to the drawing in detail, like parts being designated by like reference characters, a portion of a railway vehicle underframe is illustrated involving center or draft sills 1 to which are preferably applied double slotted cheek plates 2. The outer ends of said sills may as usual be connected to a striking casting or combined striking casting and sill tie member and intermediate portions thereof may be connected by backstop

or center filler castings (not shown) which are well known in the art.

45 Disposed between the sills 1 is the stem 3 of a coupler 4. Said coupler is of the type shown in Patent No. 1,431,717 to Donald S. Barrows in that it has a swivel block or pivotally connected butt portion 5 receiving the rearmost or inner end of the stem 3. The connection between the stem and swivel block 5 is, in the present embodiment, effected by a pin 6 held in position by flat cot- 5 ters 7 extending between lugs 8 on the upper and lower surfaces of the swivel block 5 and received in notches 9 in the end of said pin. The stem 3 of the coupler 4 is formed with rearwardly ex- 10 tending flanges or webs 10 and 11 embraced be- 15 tween or intercalated with respect to correspond- 20 ing flanges or webs 12, 13 and 14, the rear edges of the flanges 10 and 11 and engaged surfaces on the swivel block being coaxially curved with re- 25 spect to the pivot pin 6 or apertures through 30 said flanges for receiving said pin. The rear- 35 most face of the swivel block 5 is preferably aper- 40 tured or pocketed, as indicated at 15, for receiv- 45 ing the forwardly extending lug 16 on the asso- 50 ciated front follower 17.

The stem of the articulated or two part coupler assembly is formed with a slot 18 preferably par- 55 tially disposed in the intermediate flange or web 13 on the swivel block and partially in the stem proper 3 of the coupler for receiving the draft 30 key 19 for connecting said coupler 4 with the as- 35 sociated yoke 20. The ends of said key are re- 40 ceived in corresponding slots in the cheek plates 2 or draft sills 1 of the vehicle. That portion of the slot 18 in the stem 3 is enlarged to provide 45 the pocket 21 in which is received a shim 22 pref- 50 erably notched at 23 for receiving the front edge of the key 19 and curved preferably coaxially with respect to the pivot pin 6 at its front face 24, as well as its rear face which preferably nests with 55 the front face of the flange 13 of the swivel block, the engaging surface on the stem 3 being corre- 60 spondingly curved for permitting angling of the coupler with respect to the shim. The shim 22 thereby functions as a curved bearing portion at 65 the forward side or edge of the key adapted to cooperate with a correspondingly curved portion of the coupler for permitting angling there- 70 tween.

75 From the foregoing, it will be seen that I have devised a coupler with an articulated stem per- 80 mitting horizontal angling with respect to an associated yoke. Although in the present em- 85 bodiment I have shown a yoke of the horizontal type, it will be understood that I do not wish to 90 95

be limited to this showing, as if desired, I may employ another type of yoke. Under the action of draft forces, the associated key serves to connect the coupler to the yoke and maintain the proper alignment of the parts on account of its ends being guided in the corresponding slots in the associated cheek plates 2. Under the action of buffing forces, the coupler moves rearwardly with respect to the yoke on account of the rearward elongation of the corresponding slots in the yoke arms and cheek plates until the key engages the rearmost ends of the cheek plate slots when said key forms an abutment against which the shim 22 is stopped and, in turn, stops the coupler and thereby serves for the direct transmission of overload buffing forces from the coupler through the shim and key to the cheek plates and draft sills of the car, whether the coupler is straight or disposed at an angle with respect to the yoke, thereby protecting the front follower 17 and rearwardly disposed cushioning mechanism (not shown) from overloads and possible injury.

Having now described my invention, I claim:

1. A coupler comprising a stem portion and a swivel block pivoted thereto, said stem portion and swivel block having alternately interspaced flanges, an intermediate flange on the swivel block being slotted for receiving an associated draft key, the adjacent portion of said stem being formed with a complementary slotted portion for receiving the front edge of such a key and enlarged to accommodate a shim seating on said front edge, pivotal means connecting said stem and swivel block, the edges of said flanges being coaxial with said pivotal means, the front surface of said shim and the engaged surface on said stem being curved coaxially with said pivotal means for permitting angling between said stem and shim, and the rear surface of said shim being curved to nest with said swivel block.

2. In railway draft rigging, in combination with slotted draft sills, a yoke, cushioning mechanism embraced by said yoke, a coupler with a stem portion, a swivel block associated with said stem portion, said stem portion and swivel block comprising alternately interspaced flanges intercalated with respect to each other, the edges of said flanges being coaxial with the axis of swiveling, an intermediate flange on the swivel block being notched, that portion of said stem forwardly of said intermediate flange being provided with a rearwardly opening pocket, a draft key extending through slots in said sills and yoke and received in the notch in the swivel block and the pocket in said coupler stem, and a shim seated on the front edge of said key with a front face normally engaging the front wall of said pocket, whereby said shim is adapted to transmit buffing forces from said coupler through said key to the rear ends of the slotted portions of said sills for the protection of said cushioning mechanism, the front and rear edges of said shim being coaxial with the axis of swiveling of said block so that the coupler is adapted to swivel about said shim and the shim normally nests with the intermediate flange of said swivel block.

3. In a railway draft rigging, in combination with slotted draft sills, a yoke, cushioning mechanism embraced by said yoke, a coupler stem comprising intermeshing members, upright pivotal means passing through said members for connecting the same, upright surfaces of each intermeshing member disposed toward the other being coaxial with the pivotal means, said members being provided with a slot, a draft key extending through said slot and registering slots in said yoke and sills, the foremost of said intermeshing members being provided with a pocket, a shim seated on said draft key, provided with a forward surface curved coaxially with respect to said pivotal means to provide for angling of the coupler with respect thereto, a rear surface correspondingly curved so as to normally nest with the adjacent surface of the rearmost of said intermeshing members, and serving as a coupler stop for the protection of said cushioning mechanism upon the application of buffing forces.

4. In railway draft rigging, in combination with a yoke, cushioning mechanism embraced by said yoke, a coupler with a stem portion fitting between the arms of said yoke, said yoke and coupler stem having horizontally aligned slots, a connecting key seated in said slots, a follower disposed between said cushioning mechanism and coupler stem, separate draft and buffing equalizing members, one of said members being seated within said stem formed with substantially coaxial front and rear surfaces, and bearing upon the forward portion of said key and the other of said members being interposed between the latter and the follower, having a front surface approximately fitting, and extending from close to the coaxial rear surface of, said member bearing on the forward portion of the key to said follower and unitary upright pivotal means passing through said other member and extending from top to bottom of the stem portion of said coupler for connecting said member and coupler for simultaneous movement on both buff and draft.

5. In railway draft rigging, in combination with a yoke, cushioning mechanism embraced by said yoke, a coupler with a stem portion fitting between the arms of said yoke, a connecting key passing through slots in said coupler stem and yoke, a buffing equalizing member seated within said stem, formed with substantially coaxial front and rear surfaces, and bearing upon said key, and a separate draft equalizing member interposed between said stem and the cushioning mechanism, said buffing equalizer member being bifurcated to form rearwardly extending flanges embracing the forward portion of the key and extending close to the forward portion of said draft equalizing member, said draft equalizing member having its forward surfaces approximately coaxial with the adjacent surfaces on the buffing equalizing member, and unitary upright pivotal means passing through said draft member and extending from top to bottom of the stem portion of said coupler for connecting said member and coupler for simultaneous movement on both buff and draft.

NORMAN B. AKITT.
